(12) **United States Design Patent**
Wackwitz et al.

(10) **Patent No.:** **US D653,523 S**
(45) **Date of Patent:** **** Feb. 7, 2012**

(54) **ADAPTER FOR A TOOL**

(75) Inventors: **Jeffrey M. Wackwitz**, Waukesha, WI (US); **Jeff P. de Guzman**, Brookfield, WI (US)

(73) Assignee: **Milwaukee Electric Tool Corporation**, Brookfield, WI (US)

(**) Term: **14 Years**

(21) Appl. No.: **29/375,916**

(22) Filed: **Sep. 29, 2010**

(51) LOC (9) Cl. **08-05**

(52) U.S. Cl. **D8/354; D15/138**
